US0D1082495S

(12) **United States Design Patent** (10) **Patent No.:** **US D1,082,495 S**
(45) **Date of Patent:** **** Jul. 8, 2025**

(54) **CLIP FOR FLOOR PANELS**

(71) Applicant: **Välinge Innovation AB**, Viken (SE)

(72) Inventors: **Karl Quist**, Höganäs (SE); **Robin Mellby**, Påarp (SE); **Carl-Filip Sewring**, Viken (SE)

(**) Term: **15 Years**

(21) Appl. No.: **35/521,570**

(22) Filed: **Jun. 10, 2024**

(80) **Hague Agreement Data**

Int. Filing Date: **Jun. 10, 2024**

Int. Reg. No.: **DM/238105**

Int. Reg. Date: **Jun. 10, 2024**

Int. Reg. Pub. Date: **Jul. 5, 2024**

(30) **Foreign Application Priority Data**

Dec. 21, 2023 (EM) 015045327-0001

(51) **LOC (15) Cl.** **08-08**

(52) **U.S. Cl.**

USPC **D8/349**

(58) **Field of Classification Search**

(57) **CLAIM**

The ornamental design for a clip for floor panels as shown and described.

DESCRIPTION

1. Clip for floor panels

1.1 : Perspective

1.2 : Top

1.3 : Front

1.4 : Back

1.5 : Right

1.6 : Left

Clip for floor panels.

1 Claim, 6 Drawing Sheets
